UNITED STATES PATENT OFFICE.

CHARLES FREIHOFER AND FREDRICK HANSON, OF PHILADELPHIA,
PENNSYLVANIA.

DESIGN FOR A LOAF OF BREAD OR SIMILAR ARTICLE.

SPECIFICATION forming part of Design No. 33,610, dated November 20, 1900.

Application filed October 19, 1900. Serial No. 33,658. Term of patent 14 years.

To all whom it may concern:

Be it known that we, CHARLES FREIHOFER and FREDRICK HANSON, citizens of the United States, and residents of Philadelphia, Pennsylvania, have invented and produced a certain new and original Design for a Loaf of Bread or Similar Article, of which the following is a specification.

Our design for a loaf of bread or similar article is clearly illustrated in the accompanying drawing, which represents the loaf in perspective.

The essential feature of the design is the quadrangular shape of the loaf, having corrugated edges and ornamented on its upper surface.

A is the loaf of bread, quadrangular in cross-section and having a series of curved corrugations

gations *a* at each side, as illustrated in the drawing. The upper surface is rounded and has a slight division-mark *b*, and on each side of the division-mark is the representation of a spread eagle *d* and a flag *c*.

We claim—

The design for a loaf of bread or similar article, as herein described and as shown in the accompanying drawing.

In testimony whereof we have signed our names to this specification in the presence of two subscribing witnesses.

CHAS. FREIHOFER.
FREDRICK HANSON.
